SHOWCASE

Ellsworth G. Nichols, Winchester, Mass.

Application June 24, 1954, Serial No. 31,148

Term of patent 14 years

(Cl. D80—11)

Fig. 1.

Fig. 2.

Fig. 3.

Fig. 4.

To all whom it may concern,

Be it known that I, Ellsworth G. Nichols, a citizen of the United States of America, residing at Winchester, Massachusetts, have invented a new, original, and ornamental Design for a Showcase, of which the following is a specification, reference being made to the accompanying drawings, forming a part hereof.

I claim:

The ornamental design for a showcase, as shown.
